FERNAND HOUGET, OF VERVIERS, AND LOUIS RAHIER, OF ENSIVAL-VERVIERS, BELGIUM, ASSIGNORS TO SOCIÉTÉ ANONYME VERVIETOISE POUR LA CONSTRUCTION DE MACHINES, OF VERVIERS, BELGIUM.

ACTUATING MEANS FOR THE HEDDLE-FRAMES OF WEAVING-LOOMS.

1,090,536.

Specification of Letters Patent. Patented Mar. 17, 1914.

Application filed November 25, 1911. Serial No. 662,385.

To all whom it may concern:

Be it known that we, FERNAND HOUGET and LOUIS RAHIER, both subjects of the King of Belgium, residing, respectively, at 5 Verviers and at Ensival-Verviers, in the Kingdom of Belgium, have invented new and useful Improvements in Actuating Means for the Heddle-Frames for Weaving-Looms, of which the following is a specification.

This invention relates to improvements in and connected with heddle frames for looms in which the heddle frames are actuated solely from below for instance by means of 15 racks and toothed pinions and in which the frames are fixed on cross bars extending under the entire length of said frames.

The present invention has for its object to provide particularly simple and practical 20 means for effecting, as desired, the setting in place and removal or replacement of the heddle frames when they are actuated from beneath for instance by means of pinions and racks.

With this end in view the invention consists in that the heddle frames are fixed on 25 the cross bars, which extend under said frames by means of connecting members fixed to the lower cross bar of the frame 30 and coöperating with similar members fixed to the cross bar extending under the heddle frame, each of said members being provided with projecting ends and a recess adapted to receive the corresponding projections on 35 the other member.

The accompanying drawings illustrate by way of example one embodiment of the invention.

Figure 1 illustrates the mechanism actuated by rack and pinions. Fig. 2 is a separate side elevation on enlarged scale of the connecting members or locking parts of the heddle frame with the actuating cross bar. Fig. 3 is a plan view of Fig. 2.

In Fig. 1 is shown the heddle frame 1 carrying the heddles 2 through which pass the warp threads. In conformity with the invention, 3 is a cross bar extending longitudinally on which the heddle frame 1 is attached by means of connecting members or locking parts 4, 5, 6, and 7. Each bar 3 is provided with two racks 8 and 9 respectively engaging toothed wheels 10 and 11 pivotally mounted on the fixed spindles 12

and 13; the wheel 11 engaging with the rack 55 8 and the wheel 10 with the rack 9, while the two toothed wheels 10 and 11 are set in rotation by a rod 14 carrying at each end a toothed part also engaging with the toothed wheels 10 and 11. The rod 14 is supported 60 by guides 15 and 16, whereas the racks 8 and 9 are guided by fixed pins 17 and 18. The movement of the rod 14 may be effected in any convenient manner, for instance by a vertical hook 19 carrying a toothed part 65 engaging with the wheel 10, said hook receiving the desired up and down movement by suitable driving means, *i. e.*, by knives of the type frequently used in weaving 70 looms.

The heddle frames are guided at the sides thereof by pins 20 carried in supports 21 adapted to be displaced on the lugs 22 so as to approach the uprights of the heddle frames 1 or move away from said uprights 75 and approach the lugs 22 of the loom in order to disengage the heddle frames 1 which may of course be guided in any convenient manner so as to prevent their rocking at 80 right angles to their plane.

When it is necessary to replace the set of heddle frames by another set appropriate to the new cloth desired to be manufactured, it suffices to displace the left hand support 21 to the left toward the lug 22 situated 85 on the same side so as to move the guides 20 on this side away from the upright of the heddle frame. The heddle frames 1 are then moved toward the left hand lug 22 and by this means the locking members 4, 90 5, 6 and 7 are disengaged from one another so that it is only necessary to lift the heddle frames out of the loom. The setting in position of the new set of heddle frames is effected in the same manner. They are placed 95 in the loom and held slightly toward the side of the loom where the guides 20 are disengaged and are then pushed so that the locking members 4 and 6 approach the locking members 5 and 7. In view of the 100 special form of these locking members, as hereinafter described, the attachment of the heddle frames 1 on the bars 3 can be easily effected in the determined position. It is then only necessary to replace the support 105 21 of the pin guides 20 which prevents the displacement of the heddle frame and the disengagement of the locking members.

Figs. 2 and 3 show separately the locking members or attachment parts. The locking members 4 and 6 are attached to the heddle frame 1, whereas the locking members 5 and 7 are fixed to the bar 3. The locking members have each a projection A which can engage in the other locking member and at the end of the projection is a recess B which at the instant when two corresponding locking members are pushed one into the other receives a projection C of similar form to the recess. The projections A thus rigidly attach the heddle frames 1 to the bars 3; the recesses B and the projections C compel the heddles and the bars to lie flush so as not to present any projecting parts between the heddle frames. These devices consequently allow a rapid exchange of a set of heddle frames the work for which is ended, for another set of heddle frames and their instantaneous mounting in the desired position for these heddle frames in the loom.

What we claim is:

In an actuating mechanism for heddle frames of weaving looms, in combination 25 with a heddle-frame, a lower shaft for said heddle frame, an actuating bar, connecting members between the lower shaft of the heddle frame and the actuating bar, said members comprising two parts, one fixed to 30 the heddle-frame and the other on the actuating bar, each of said parts being provided with a projection and recess, and means including a rack and toothed wheel drive for actuating said bar, substantially as de- 35 scribed.

In testimony whereof we have signed our names to this specification in the presence of two subscribing witnesses.

FERNAND HOUGET.
LOUIS RAHIER.
